[57] CLAIM

The ornamental design for a portable computer housing, as shown and described.

DESCRIPTION

FIG. 1 is a right, front, top perspective view of a portable computer housing embodying our new design; FIGS. 2, 3, 4 and 5 are respectively front, left side, right side and rear elevation views thereof;

FIGS. 6 and 7 are respectively bottom and top plan views thereof;

FIG. 8 is a bottom plan view thereof with the handle shown in a carrying position;

FIG. 9 is a right side elevation view thereof;

FIG. 10 is a right, front, top perspective view of the portable computer housing of FIG. 1 with the top, front section of the housing opened to a viewing position and rear cover plate rotated to a pedestal position;

FIGS. 11, 12, 13 and 14 are respectively front, left side, right side and rear elevation views of the housing as shown in FIG. 10;

FIGS. 15 and 16 are respectively bottom and top plan views of the housing as shown in FIG. 10; and

FIG. 17 is a right, front, top perspective view of the housing as shown in FIG. 10 with the front, top section tilted to an alternate position.
